UNITED STATES PATENT OFFICE.

ROBERT C. CLARKE, OF LAUREL, NEW YORK.

TIMER.

Application filed March 3, 1921. Serial No. 449,308.

To all whom it may concern:

Be it known that I, ROBERT C. CLARKE, a citizen of the United States, and resident of Laurel, in the county of Suffolk and State of New York, have invented certain new and useful Improvements in Timers, of which the following is a specification.

This invention relates to timers for the ignition means employed with internal combustion motors, and my improvements are directed to a device of this character having relatively few parts, and wherein the operative elements are positive in their actions.

In my improved timing device the rotor, which is carried by an engine driven shaft, and which is provided with a peripheral contact, is revoluble in constant engagement with the several individual spring contact elements which represent the ignition circuits for the different cylinders, whose pressure upon the rotor contact, to close the respective ignition circuits, occurs through a smoothly guided or wiping co-action between said rotor contact and said spring contacts without shock or jar such as would tend toward excessive wear in operation.

Further, by according a curvature to that portion of the spring contact which is to co-act with the rotor contact, a dwell surface is provided which prolongs the period of excitation for the individual cylinder ignition circuits. This is of particular importance where the electrical discharge flows from spark coils having vibrators as will be readily appreciated.

The rotor, which is composed of suitable insulation material, as fibre for example, may be provided with peripheral, anti-frictional means to avoid undue wear between said rotor and the spring contacts with which it is in constant revoluble engagement.

Other features and advantages of my invention will hereinafter appear:

In the drawing:

45 Figure 1 is a side sectional elevation of my improved timer.

Fig. 2 is a front section on the line 2—2 of Figure 1.

Fig. 3 is a cross-section through the rotor, 50 and

Fig. 4 is a side elevation of the rotor.

In the example of my invention illustrated in the accompanying drawing, let 1 indicate the usual timing shaft of an internal combustion engine, and 2 a rotor element, composed of fibre or some other suitable insulating ma-

terial, said rotor having a slot 3 for the reception of a pin 4 that is entered in an orifice provided therefor in shaft 1, to key the rotor to the shaft; and said rotor having a partly cylindrical groove 5 formed transversely therein, open at one end and exposed through the peripheral surface of said rotor.

Said groove 5 is intended for the reception of a cylindrical contact element 6, which fits snugly therein, but is capable of rotation for purposes of adjustment. A surface portion of contact 6 protrudes through the peripherally exposed portion of groove 5, to thus be in position for service. The contact 6 has a diminished end portion 7 that projects beyond the end of the rotor, and a disk 8, that fits over shaft 1, has an orifice 9 to receive end portion 7 and electrically engage it and the unreduced end surface of said contact, also securing the latter in its operative position within the rotor. Also disk 8 is provided with an orifice 9^a for the engaging reception on an angled portion of pin 4. Thus the disk 8 comprises a localizing cap for contact 6 and pin 4, and is itself secured upon the shaft by a nut 9^b.

The timer casing is in two parts 10 and 11, which are capable of removably fitting together in any known manner. The part 10, which may be provided with a control fitting 12, has secured therein a number of spring contact elements 13, each connecting with a separate binding post 14, and adapted to successively effect a wiping contact with element 6. While four of these spring contact elements 13 are herein shown, this is of course a purely arbitrary number thereof, for use with the ignition circuits, respectively, of an engine having four cylinders, and the number of said elements 13 may be varied at will.

The elements 13 extend inwardly of casing part 10 from its inner peripheral surface, each lying in irregular tangents from a bend 15, that springs from a flat portion 16 which engages a binding post 14. Said portion 16 is seated in a recess 17 provided in an insulation piece 18 that is secured, by the securing means for the binding post, to the wall of the casing portion 10, this seating relation of the elements 13 serving to localize them, and prevent their being accidentally shifted out of the operative transverse plane they occupy.

The spring contact elements 13 are angled so that they unitedly form an outer

bearing for rotor 2, upon whose peripheral surface the free end portions of said elements continually bear, for guidance into contact with element 6, successively, in the rotation 5 of the shaft.

Each spring contact element 13 is provided with a curved portion 18^a, adapted to prolong the period of passing contact effected by member 6, said curvature 18^a enabling the element 6 to meet elements 13 at a point in advance of the point of contact which would occur if the contact portion of elements 13 were flat, and correspondingly, the element 6 does not leave 10 electrical engagement with elements 13 until it has passed beyond said curved portion 18^a. This feature is of especial importance where a vibrator controlled coil is used and the discharge at the spark points 15 continues through the period of excitation. 20

Due to the continual engagement of elements 13 with the rotor and the easy gradient with which portions 18^a enter upon their contacting relation with element 6, the life 25 of the device is prolonged, because only a minimum of wear can occur between the parts. Besides, the action is that of a wiping contact, which is highly efficient.

As the used surface of element 6 wears 30 said element can be rotated slightly in its bearing, to present a new contact portion. For this purpose the end of portion 7 may have an exposed nick 19 for engagement by a small tool, whereby said element 6 may be 35 rotated without removal of disk 8.

The rotor 2 is provided with a peripheral groove 20, which may be filled with some lubricating material, indicated at 21, such as grease, rawhide, or other suitable substance, to minimize friction between the rotor and spring contacts in the operation of 40 the device.

Variations within the spirit and scope of 45 my invention are equally comprehended herein.

I claim:—

1. The combination, with a timer, having an insulation rotor element with a partly cylindrical, transverse peripheral groove, 50 and a contact element presenting a segmental portion seated in said groove, said contact element projected beyond the rotor surface, of a casing, and a number of flat spring contact elements centering from 55 said casing in bearing relation with said rotor, said spring contact elements having

curved bearing surfaces to effect prolonged engagement with said rotor contact.

2. A timer comprising a shaft, a rotor of insulation material carried thereby, said rotor having a partly cylindrical, transverse peripheral groove, a cylindrical contact element fitted in said groove and projecting from the peripheral surface of the rotor, a casing, and a number of spring contact elements carried by said casing, said spring contact elements bearing normally against said rotor to successively engage said cylindrical contact element with wiping contact. 60 65

3. A timer comprising a shaft, a rotor of insulation material carried thereby, said rotor having a partly cylindrical, transverse peripheral groove, a revolvably adjustable, cylindrical contact element fitted in said groove and projecting from the peripheral 70 surface of the rotor, a casing, and a number of spring contact elements carried by said casing, said spring contact elements bearing normally against said rotor to successively engage said cylindrical contact element with 75 wiping contact. 80

4. A timer comprising a shaft, a rotor of insulation material carried thereby, said rotor having a partly cylindrical, transverse peripheral groove, a contact element removably fitted within said groove and having a segmental operative portion projected beyond the peripheral surface of said rotor, a casing, a number of spring contact elements centering tangentially from the peripheral wall of said casing and bearing normally against said rotor, said spring contact elements each having a curved bearing surface to co-act with the segmental operative portion of said rotor contact element 90 and effect prolonged passing contact therewith. 95

5. The combination, in a timer, of a rotor composed of insulation material, said rotor having a partly cylindrical, transverse peripheral groove, a contact element fitted in said groove and projecting from said rotor, a number of spring contact elements bearing continually upon said rotor, and said rotor having a peripheral groove containing lubricating material, to minimize friction between said rotor and contact springs. 100 105

Signed at the borough of Manhattan, in the city, county and State of New York, 110 this 26th day of February, A. D. 1921.

ROBERT C. CLARKE.
